UNITED STATES PATENT OFFICE.

GEORGE P. FARMER, OF MONTCLAIR, NEW JERSEY.

DESIGN FOR A GLOVE-BUTTONER.

SPECIFICATION forming part of Design No. 24,997, dated December 24, 1895.

Application filed December 10, 1894. Serial No. 531,419. Term of patent 14 years.

To all whom it may concern:

Be it known that I, GEORGE P. FARMER, a citizen of the United States, residing at Montclair, in the county of Essex, and the State of New Jersey, have invented a new and original Design for Glove-Buttoners, of which the following is a full, clear, and exact description.

The design is illustrated in the accompanying drawings, in which—

10 Figure 1 is a front elevation, and Fig. 2 an end view, of the glove-buttoner, showing my design.

15 The leading feature of the design consists in the shape and configuration as hereinafter set forth.

19 The main body of the buttoner consists of an open loop the sides of which diverge from the bend *a* to the shoulders *b*, whence they converge to the point *c*.

20 The parts of the buttoner extend parallel to one another from the point *c* to the point

d to form a narrow neck, from the upper extremity of which diverge two sides of a second loop, the two sides from the point *e* of greatest divergence extending upwardly a 25 short distance, then being bent over and extending downwardly at a slight incline and then outwardly to the common bend *f*. This downward incline and outward bulge to the common bend *f* gives to the upper portion of 30 the buttoner somewhat the shape of a shepherd's crook.

I claim as my invention—

The design for a glove buttoner substantially as shown and described.

35 In testimony whereof I have signed my name to this specification in the presence of two subscribing witnesses.

GEORGE P. FARMER.
